US0D1098010S

(12) **United States Design Patent** (10) Patent No.: **US D1,098,010 S**
(45) Date of Patent: ** Oct. 14, 2025

(54) **CHARGER**

(71) Applicant: **Shenzhen Lanhe Technologies Co., Ltd.**, Shenzhen (CN)

(72) Inventors: **Wenqing Xie**, Shenzhen (CN); **Shuaihang Li**, Shenzhen (CN)

(73) Assignee: **Shenzhen Lanhe Technologies Co., Ltd.**, Shenzhen (CN)

(**) Term: **15 Years**

(21) Appl. No.: **29/944,498**

(22) Filed: **May 28, 2024**

(30) **Foreign Application Priority Data**

Nov. 29, 2023 (CN) 202330784526.3

(57) **CLAIM**

The ornamental design for a charger as shown and described.

DESCRIPTION

FIG. 1 is a bottom perspective view of a charger showing our new design;

FIG. 2 is a top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

(Continued)

FIG. 9 is a bottom perspective view thereof, showing contact pins of the charger in a retracted state.

The broken lines in the drawings depict portions of the charger that form no part of the claimed design.

1 Claim, 9 Drawing Sheets
